TRUMP BROS. MACHINE COMPANY, OF WILMINGTON, DELAWARE, A CORPORATION
OF DELAWARE

KNITTED FABRIC AND PROCESS OF MAKING SAME

Application filed February 20, 1929. Serial No. 341,374.

It is known to knit plated fabric formed of three threads, namely, a plating thread which is normally on the face, a backing thread which is normally on the back, and a middle thread which is normally in the middle; all knit into the fabric in plating relation. It is also known to bring the backing thread onto the face of the fabric either by reversing or otherwise changing the order of the threads while maintaining them in plating relation. It is also known to bring the middle thread onto the face of the fabric by reversing or otherwise changing the order of the threads while maintaining them in plating relation; also by knitting in the middle thread and the plating thread in reverse plating relation and floating the backing thread; also by knitting in only the middle thread and floating the other threads.

Thereby three color striped and figured effects and designs of great variety can be produced.

The effects produced by knitting in the three threads in a different order so as to bring the backing thread or the middle thread to the face is not identical with the effect produced by bringing the backing thread or the middle thread to the face and floating one or both of the other threads. One object of my invention is to provide a fabric in which, in certain parts thereof, one of the threads is on the face in plating relation to the other threads, while in other parts thereof the same thread is on the face while one of the other threads floats. Thereby not only can three color effects be produced, but variations of a single color effect can be produced. In the drawings and following description, one example of such a fabric is disclosed.

Heretofore, in knitting three color fabrics as above described, the threads are manipulated by deflecting selected needles in the yarn drawing operation, by prematurely depressing selected needles to cause them to escape engagement with one or two threads, or by both operations combined; and the positioning of the plating thread on the face in normal plating has been effected by imposing a greater tension on that thread than

on the other two threads. The premature depression of certain needles has been effected by providing such needles with shoulders of different width, which are actuated by a specially constructed radially movable cam, 55 whose action in drawing down a given shouldered needle either at the normal time or prematurely depends on its radial position and on the width of the needle shoulder. Such shouldered needles must be constructed 60 with the greatest accuracy, since a slight departure from the calculated width of the shoulders renders the operation uncertain any may produce fabric in which the designs are defective. Another and important object of the invention is to simplify the method of causing a thread to escape engagement with selected needles, and to avoid the use of specially constructed shouldered needles and specially constructed actuating cams. 70

The fabric herein described and shown cannot be produced, it is believed, on any known machine except that herein disclosed, nor is it believed that such a fabric can be produced by merely aggregating old mechanisms or methods for performing the operations hereinafter particularly described. 75

In order that those skilled in the art may produce my improved fabric without the necessity of experimentation, I shall describe part of a circular knitting machine and mechanism applied thereto, which are adapted, during the ordinary up and down operation of the needles by the usual cams, to carry out the process I have devised for 80 producing said fabric. In the drawings, to which reference will be made in the description:—

Fig. 1 is a diagram of part of a circle of needles, the yarn feed and the usual needle 90 actuating cams.

Fig. 2 is an elevational view, mainly in vertical section, of a part of a needle cylinder and of the means for deflecting the needles which it is preferred to use in carrying out 95 the process.

Fig. 3 is a diagram of a small section of fabric embodying my invention; the same being enlarged and the openings between threads being relatively still more enlarged 100

in order to more clearly show the construction.

Fig. 4 is a diagram showing the relative positions of the threads in the parts of Fig. 3 immediately below it.

Fig. 5 is a plan view, more or less diagrammatic, of an arc of the needle cylinder, the yarn feed and the cams for selectively actuating the needle deflecting means.

Fig. 6 is a view similar to Fig. 5 showing a modification.

Three differently colored threads *a*, *b* and *c* are fed toward the needles. Threads *b* and *c* may be fed from a yarn carrier *e*, which may be positioned about where it is common to position yarn carriers in ordinary knitting or in the knitting of plated fabric. Greater tension is imposed on yarn *b* than on yarn *c* so that yarn *b*, when knitted into the fabric, will overlie yarn *c*. The thread *a* may be fed from a yarn carrier *d*. The point of feed of thread *a* to the needles is behind (relative to the direction of rotation of the needle cylinder) the point of feed of threads *b* and *c* to the needles. Carrier *d* is located closer than carrier *e* to the circle of needles. A greater tension may be imposed on thread *a* than on threads *b* and *c* so as to insure that thread *a* will be knit into the fabric inside threads *b* and *c*, in order that in the finished plated fabric thread *a* will appear on the face or outside, as shown in the two wales I of Fig. 3. It is unnecessary, however, to impose a substantially greater tension on thread *a* than on threads *b* and *c*, since the point of feed of thread *a* from carrier *d* is so close to the circle of needles that, in the rotation of the needle cylinder, it will be carried over, and drawn frictionally against, the outside of the shanks of a number of needles before it is engaged by the descending hook of a needle and knitted into the fabric; so that it will naturally strongly tend to remain on the inside during knitting and therefore appear on the face or outside of the finished fabric.

However, in feeding thread *a* to the needles as shown in Figs. 1 and 5, it will actually be fed to the inside of the normal needle circle and altogether escape engagement with the hooks of the needles in the subsequent yarn drawing movement (which occurs at a point considerably in advance of the point of feed of thread *a*) unless special means are provided to prevent such mode of operation. In order to cause thread *a* to be carried around the outside of the circle of needles, the needles are deflected radially inward at the point *f*², Fig. 5, that is, at such point, approximately opposite the point of feed from carrier *d*, that the thread will be fed outside the deflected needles and will, after such deflected needles spring back to normal position, remain on the outside of, and be drawn against, the shanks of the needles before the

thread is engaged by the needle hooks in the yarn drawing operation.

In order to reverse plate, that is, to knit a plated fabric in which the above described order of the threads is reversed, the hook ends of selected needles *f*³ are deflected radially inward in proper timed relation to the yarn drawing movement and to the casting off point. This, per se, is a known method of operation. In the finished fabric thread *c* appears on the face, thread *b* in the middle, and thread *a* on the back, as shown in the two wales II of Fig. 3 and the part of Fig. 4 immediately above those wales.

In order to knit a fabric in which thread *b* appears on the face, the hook ends of selected needles *f*³ are not deflected inward at the point *f*², Fig. 5, with the result that thread *a* is carried back of such needles and, in the subsequent yarn drawing movement of such needles, is not engaged by the hooks thereof, whereby thread *a* is not knit into the fabric but floats back of the same, as illustrated in wales III of Fig. 3 and the part of Fig. 4 immediately thereabove.

In order to knit a fabric in which thread *c* appears on the face and thread *a* floats, the hook ends of selected needles *f*³ are not deflected inward at the point *f*², Fig. 5, with the result that thread *a* is carried back of such needles and, in the subsequent yarn drawing movement, is not engaged by the hooks thereof. The hook ends of the same selected needles are deflected radially inward in proper timed relation to the yarn drawing movement and to the casting off point. This effects a reversal of the normal positions of threads *b* and *c*, so that thread *c* appears on the face in plating relation with thread *b*, while thread *a* floats at the back, as illustrated in wales IV of Fig. 3 and the part of Fig. 4 immediately thereabove.

In order to selectively bend back needles it is preferred to utilize the mechanism disclosed and claimed in an application filed by me July 29, 1927, Serial No. 209,393. This mechanism is shown in Fig. 2. The needles *f* are moved up and down in a normal knitting wave by cams *g* operating in the usual way. Fastened to the needle cylinder is the sinker dial *h*, which carries the sinkers or web holders *i*, which cooperate with the needles in the usual manner to form the stitches.

Below the sinker dial *h* is a slotted jack dial *j*, which is attached to the sinker dial. Pressers *k* are placed in the needle cylinder slots after the needles have been inserted and are held in place by the two spring bands *m*. These pressers are so shaped that they bear against the needles at the extreme upper ends of the pressers and also at points opposite the spring bands *m*. The needle cylinder slots are of greater than normal depth at their upper ends, forming shoulder *n*. The needles

are unsupported above these shoulders, which act as fulcrums when needles are pushed back by the upper ends of pressers *k*. The jack dial *j* has slots corresponding in number with 5 the slots in the needle cylinder. At intervals and in groups in accordance with a pattern which is to be formed in the knitted fabric, jacks *o* are inserted in the dial slots. These jacks are held lightly in contact with their 10 corresponding needle pressers *k* by a spring band *p*.

A threaded clamp ring *q* holds the jacks in their proper vertical position. The jacks are formed with slots on their rear ends so 15 that sections may be broken out in different places, leaving butts *r*, which may be in any one of any number of (say eight) different vertical positions.

The cams *s*, *s'* for operating the butts *r* 20 should correspond in number to the number of vertical positions of the butts. Each cam is in alignment with one of the corresponding butt locations on jacks *o*. These cams do not revolve and may be moved, by appropriate 25 pattern mechanism known in the art, into and out of the paths of the butts *r* of jacks *o*.

When one or more of the cams *s* or *s'* are moved and held in the path of jacks *o* having butts *r* corresponding to the vertical positions 30 of such cams, these jacks will be pushed inward and will in turn rock the corresponding pressers or pushers *k*, thereby springing the corresponding needles *f* at the fulcrum points *n*, causing their hooked ends to be bent back out of line with adjacent undeflected 35 needles in the normal knitting plane.

Since provision must be made for deflecting both selected needles *f'* and also all of the needles (except when thread *a* is to be 40 floated) at point *f*², two sets of needle deflecting mechanisms, including two sets of cams *s*, *s'* are provided. In Fig. 5, the top cam of one set of cams is lettered *s*, while the top cam of the other set of cams is lettered 45 *s'*. The two sets of cams are similarly lettered in Fig. 2. It will be understood that in an accurate section through either of the two needle deflecting mechanisms, only one set of cams, *s* or *s'*, could appear; but both 50 sets of cams are shown in Fig. 2 in order to illustrate their respective vertical positions and make clear how they act independently on the butts *r* of jacks *o*.

By means of the described needle deflecting 55 mechanism, any needle may be deflected inward or bent back at either point *f*² or at the stitch forming point, or at both points, at any course of knitting, whereby, if threads *a*, *b* and *c* are of different colors, nor only stripes, 60 but designs of indefinite variety, in three colors, may be produced in any desired parts of the fabric. Different modifications of a single color may be produced by, for example, knitting thread *c* in plating relation to both 65 the other threads (wales II, Figs. 3) or in

plating relation to only thread *b*, while thread *a* floats (wales IV, Fig. 3).

One of the pronounced advantages of the invention is the fact that reverse plating and floating are both produced by the same kind of operation, namely, by deflecting needles radially inward. This kind of operation presents decided advantages over any other known kind of operation for producing either effect. It is true that needles have been deflected radially inward to produce reverse plating and it is also true that needles have been deflected radially outward to cause the needle to miss the yarn; but my invention does not involve the mere, or any, association in one machine of two old mechanisms. Nor is the mode of operation the same as would occur if it were possible to associate in one machine the two old mechanisms. In my invention all the needles are deflected radially inward at one point in the needle circle, whether it is intended to effect normal plating or reverse plating of all three threads; while selected needles are not so deflected, at the same point in the needle circle, when it is intended that one thread shall float. Neither normal three thread plating nor reverse three thread plating can be effected unless the needles are previously deflected, and to effect reverse three thread plating, the needles must be deflected twice at spaced apart points in the circle of needles.

The invention is not limited to a fabric comprising only three threads so long as it comprises a fabric containing at least three threads. Thus, as shown in Fig. 6, a fourth thread *x*, as well as thread *a*, may be fed toward the needles a substantial distance back of the point at which the yarn is drawn down to form loops. The fourth thread may be fed toward the needles in the same way that thread *a* is fed toward the needles but at a different point in the needle circle; and whether or not the fourth thread shall be knit into the fabric by a given needle will depend on whether or not such needle is deflected at the thread-feeding point. This involves a mere duplication of the yarn feed and needle deflecting devices shown herein for determining the engagement with a needle of thread *a*. It is clear that if the fourth thread *x* is, for example, subjected to greater tension than the thread *a*, it will, if knit into the fabric by a certain needle, appear on the face of the fabric in normal plating, whereas if it is not knit into the fabric thread *a*, if knit into the fabric, will appear on the face in normal plating; that in reverse plating thread *c* will appear on the face of the fabric; and that if neither thread *a* nor the fourth thread *x* is engaged by a needle hook, thread *b* will appear on the face of the fabric in normal knitting.

Having now fully described my invention,

what I claim and desire to protect by Letters Patent is:—

1. A knitted fabric composed of three threads and comprising stitched loops, in some of which all three threads are in plating relation with the threads arranged in a certain order, in others of which all three threads are in plating relation with the threads arranged in the reverse order, in others of which two threads are in normal plating relation while the third thread floats and in others of which the same two threads are in reverse plating relation while the said third thread floats.

2. A knitted fabric composed of three threads, namely, a plating thread, a backing thread and a middle thread, and comprising stitched loops in which all three threads are in plated relationship and in some of which the plating thread appears on the face and the backing thread on the back and in others of which the positions of said two threads are reversed, other stitched loops composed of the middle thread and the backing thread in plating relationship in which the middle thread appears on the face over the backing thread and the plating thread floats, and other stitched loops composed of the middle thread and the backing thread in plated relationship in which the backing thread appears on the face over the middle thread and the plating thread floats.

3. The process of knitting a plated fabric upon a circular series of independent needles which comprises so knitting into the fabric two threads that normally one thread will be on top of and in plating relation with the other in the knitted fabric, feeding a third thread toward the needles a substantial distance back of the point at which the yarn is drawn down to form loops, and causing said third thread to be drawn arcuately across and in frictional contact with the outside of successive needles before reaching the point of yarn drawing movement, whereby said third thread will be held at the inside of the needle hooks during the yarn drawing movement and will appear on the face of the finished fabric in plating relation to the other two threads, and so manipulating the needles as to cause said third thread to be engaged by the hooks of certain needles and escape engagement with the hooks of certain needles and during the knitting operation, while only two threads are being acted upon in plating relation, and also while all three threads are being acted upon in plating relation, deflecting selected needles at the thread receiving end to reverse the specified plating order of the threads.

4. The process of knitting a plated fabric upon a circular series of independent needles which comprises so knitting into the fabric two threads that normally one thread will be on top of and in plating relation with the other in the knitted fabric, feeding a third thread toward the needles a substantial distance back of the point at which the yarn is drawn down to form loops and causing said third thread to be drawn arcuately across

and in frictional contact with the outside of successive needles before reaching the point of yarn drawing movement, whereby said third thread will be held at the inside of the needle hooks during the yarn drawing movement and will appear on the face of the finished fabric in plating relation to the other two threads, and so manipulating the needles as to cause said third thread to be engaged by the hooks of certain needles and escape engagement with the hooks of certain needles and during the knitting operation, while a plurality of threads are being acted upon in plating relation, deflecting selected needles at the thread receiving end to reverse the specified plating order of the threads.

5. The process of knitting a plated fabric upon a circular series of independent needles which comprises so knitting into the fabric two threads that normally one thread will be on top of and in plating relation with the other in the knitted fabric, feeding a third thread toward the needles a substantial distance back of the point at which the yarn is drawn down to form loops, and causing said third thread to be drawn arcuately across and in frictional contact with the outside of successive needles before reaching the point of yarn drawing movement, whereby said third thread will be held at the inside of the needle hooks during the yarn drawing movement and will appear on the face of the finished fabric in plating relation to the other two threads, and so manipulating the needles as to cause said third thread to be engaged by the hooks of certain needles and escape engagement with the hooks of certain needles and during the knitting operation, while only two threads are being acted upon in plating relation, and also while all three threads are being acted upon in plating relation, deflecting selected needles at the thread receiving end to reverse the specified plating order of the threads.

6. The process of knitting a plated fabric upon a circular series of independent needles which comprises so knitting into the fabric two threads that normally one thread will be on top of and in plating relation with the other in the knitted fabric, feeding a third thread to the inside of the circle of normally positioned needles at a point a substantial distance back of the point at which the yarn is drawn down to form loops so that said third thread will subsequently escape engagement with the hooks of needles which were so normally positioned at the feed point, and deflecting inwardly selected needles to cause said third thread to feed to the outside of such needles and hug the needles and be in position to be engaged by the hooks of such needles in their yarn drawing movement, whereby said third thread, when engaged by the hooks of selected needles, will appear on

- the face of the finished fabric in plating relation to the first two named threads and, when escaping engagement with the hooks of needles which were not so deflected, will float 5 at the back of the fabric.
7. The process of knitting a plated fabric upon a circular series of independent needles which comprises so knitting into the fabric two threads that normally one thread will be 10 on top of and in plating relation with the other in the knitted fabric, feeding a third thread to the inside of the circle of normally positioned needles at a point a substantial distance back of the point at which the yarn is 15 drawn down to form loops so that said third thread will subsequently escape engagement with the hooks of needles which were so normally positioned at the feed point, and deflecting inwardly selected needles to cause said 20 third thread to feed to the outside of such needles and hug the needles and be in position to be engaged by the hooks of such needles in their yarn drawing movement, whereby said third thread, when engaged by the hooks of 25 selected needles, will appear on the face of the finished fabric in plating relation to the first two named threads and, when escaping engagement with the hooks of needles which were not so deflected, will float at the back of 30 the fabric, and during the knitting operation, while a plurality of threads are being acted upon in plating relation, deflecting selected needles at the thread receiving end to reverse the specified plating order of the threads.
- 35 8. The process of knitting a plated fabric composed of three threads upon a circular series of independent needles which comprises feeding two threads at about the stitch forming point, feeding a third thread at an 40 earlier point in the needle circle and so manipulating needles at both points that each of the three threads is caused to appear on the surface in different parts of the fabric in plated relationship with at least one of the 45 other threads.
9. The process of knitting a plated fabric composed of three threads upon a circular series of independent needles which comprises feeding two threads at about the stitch 50 forming point, feeding a third thread at an earlier point in the needle circle and so deflecting needles at both points that each of the three threads is caused to appear on the surface in different parts of the fabric.
- 55 10. The process of knitting a plated fabric composed of three threads upon a circular series of independent needles which comprises feeding two threads at about the stitch forming point, feeding a third thread at an earlier point in the needle circle and so manipulating needles at both points that each of the three threads is caused to appear on the surface in different parts of the fabric in plated relationship with at least one of the 60
- other threads and that in certain parts of the fabric one of said threads floats.
11. The process of knitting a plated fabric composed of three threads upon a circular series of independent needles which comprises 70 feeding two threads at about the stitch forming point, feeding a third thread at an earlier point in the needle circle and so deflecting needles at both points that each of the three threads is caused to appear on the surface in different parts of the fabric and that in certain parts of the fabric one of said threads floats. 75
12. A knitted fabric including at least three threads extending continuously along successive courses of the fabric, said fabric having a portion in which all three threads are knit into loops in which one of said threads overlies the second and third of said threads and the second thread overlies the third, and another portion in which the first and second threads are knit into loops with the first thread overlying the second and in which the third thread floats. 80
13. A knitted fabric including at least 90 three threads extending continuously along successive courses of the fabric, said fabric having a portion in which all three threads are knit into loops in which one of said threads overlies the second and third of said threads and the second thread overlies the third, another portion in which all three threads are knit into loops in which the third thread overlies the second and first threads 95 and the second thread overlies the first thread, and still another portion in which the first and second threads are knit into loops with the first thread overlying the second and in which the third thread floats. 100
14. A knitted fabric including at least 105 three threads extending continuously along successive courses of the fabric, said fabric having a portion in which all three threads are knit into loops in which one of said threads overlies the second and third of said threads and the second thread overlies the third, another portion in which the first and second threads are knit into loops with the first thread overlying the second and in which the third thread floats, and still another portion in which the first and second threads are knit into loops with the second thread overlying the first and in which the third thread floats. 110
15. A knitted fabric including at least 115 three threads, said fabric having a portion in which all three threads are knit into loops in which one of said threads overlies the second and third of said threads and the second thread overlies the third, and another portion in which the first and second threads are knit into loops with the second thread overlying the first and in which the third thread floats. 120
16. A knitted fabric including at least 125 three threads, said fabric having a portion

in which all three threads are knit into loops in which one of said threads overlies the second and third of said threads and the second thread overlies the third, another portion in which all three threads are knit into loops in which the third thread overlies the second and first threads and the second thread overlies the first thread, and still another portion in which only the first and second of said threads are knit into loops with the first thread overlying the second.

17. A knitted fabric including at least three threads, said fabric having a portion in which all three threads are knit into loops in which one of said threads overlies the second and third of said threads and the second thread overlies the third, another portion in which only the first and second of said threads are knit into loops with the first thread overlying the second, and still another portion in which only the first and second of said threads are knit into loops with the second thread overlying the first.

18. A knitted fabric including at least three threads, said fabric having a portion in which all three threads are knit into loops in which one of said threads overlies the second and third of said threads and the second thread overlies the third, another portion in which all three threads are knit into loops in which the third thread overlies the second and first threads and the second thread overlies the first thread, still another portion in which only the first and second of said threads are knit into loops with the first thread overlying the second, and a fourth portion in which only the first and second of said threads are knit into loops with the second thread overlying the first.

In testimony of which invention, I have hereunto set my hand, at Philadelphia, Pennsylvania, on this 22nd day of January, 1929.

WILBUR L. HOUSEMAN.
